UNITED STATES PATENT OFFICE

99,019

DESIGN FOR A RECORDER HOUSING FOR DIAL SCALES

Harlan A. Hadley, St. Johnsbury, Vt., assignor to
E. and T. Fairbanks and Company, St. Johnsbury, Vt., a corporation of Vermont

Application July 15, 1935, Serial No. 57,623

Term of patent 7 years

To all whom it may concern:

Be it known that I, Harlan A. Hadley, a citizen of the United States, residing at St. Johnsbury, in the county of Caledonia and State of Vermont, have invented a new, original, and ornamental Design for a Recorder Housing for Dial Scales, of which the following is a specification, reference being had to the accompanying drawing, forming part thereof.

Figure 1 is a perspective view of a recorder housing for dial scales showing my new design.

Figure 2 is a top plan view thereof.

I claim:

The ornamental design for a recorder housing for dial scales, as shown.

HARLAN A. HADLEY.
